T. E. LEWIS.

Wagon Body.

No. 81,800.

Patented Sept. 1, 1868.

Inventor:
T. E. Lewis
per J. H. Alexander
Atty.

United States Patent Office.

THOMAS E. LEWIS, OF PENNVILLE, INDIANA.

Letters Patent No. 81,800, dated September 1, 1868.

IMPROVEMENT IN WAGON-BODIES.

The Schedule referred to in these Letters Patent and making part of the same.

TO ALL WHOM IT MAY CONCERN:

Be it known that I, THOMAS E. LEWIS, of Pennville, in the county of Jay, and State of Indiana, have invented certain new and useful Improvements in Wagon-Bodies; and I do hereby declare that the following is a full, clear, and exact description thereof, reference being had to the accompanying drawings, and to the letters of reference marked thereon, which form a part of this specification, in which—

Figure 1 represents a perspective view of my wagon-body,

Figure 2 a perspective of the same, with the bottom thrown back on its hinges, and

Figure 3 a view of the body when the sides, bed, and ends are folded together.

The nature of this invention consists in constructing the body of a wagon so that it will fold up substantially in the manner hereinafter set forth.

To enable others skilled in the art to make and use my invention, I will now describe its construction and operation.

A A represent the bed-pieces of the body of a wagon, which are connected together at their inner edges by the hinges g g, the straps of said hinges being fastened to the under side of the bed-pieces A A by means of rivets. By the use of the hinges g g, the bed-pieces can be folded, and one made to lap on the other.

B B designate the side-pieces, which are attached to bed-piece A A by hinges e e. By means of this arrangement the side-pieces can be folded inward, so as to lie flat on the bed-pieces A A.

C C represent the two end-pieces or gates, which are provided with the straps d d on their outer sides, the said straps terminating at each end in eyes which are intended to receive a rod, for the purpose hereinafter designated.

h h represent straps attached by bolts to the ends of the side-pieces B B, said straps terminating in eyes to correspond with those in straps d d. When the bottom and sides are adjusted as seen in fig. 1, and the gates C C are in position, the eyes in d d will be in a line with the eyes in h h, and a rod will be inserted in said eyes, and thus bind the end-pieces or gates C C to the side-pieces B B, which will complete the adjustment of the wagon-body.

It will be remarked that when the rod that binds one end of the gates C C to the side-pieces is removed, the gates can be folded back against said side-pieces by means of the remaining rods, which answer the purpose of hinges.

One of the advantages of my invention is, that in place of its requiring several persons to remove my wagon-body from the running-gear, one person can, by folding the bed-pieces, side-pieces, and ends together, as shown in fig. 3, do the work easily and expeditiously.

What I claim as new, and desire to secure by Letters Patent, is—

A wagon-body constructed and operating substantially in the manner described.

In testimony that I claim the foregoing as my own, I affix my signature in presence of two witnesses.

THOMAS E. LEWIS.

Witnesses:

THOMAS GRAY,
E. H. GRAY.
